(57) **CLAIM**

An ornamental design for a shower valve trim package, as shown and described.

DESCRIPTION

FIG. 1 is a front view of a shower valve trim package

FIG. 2 is a top view thereof;

FIG. 3 is a bottom view thereof.

FIG. 4 is a left side view thereof; and,

FIG. 5 is a perspective view thereof.

The broken line showing rear valve housing is included for the purpose of illustrating a portion of the shower valve that forms no part of the claimed design.
